(57) **CLAIM**

The ornamental design for a display screen or portion thereof with a graphical user interface, as shown and described.

DESCRIPTION

FIG. 1 illustrates a front view of an electronic device having a display screen, in accordance with a first embodiment. FIG. 2 illustrates a front view of an electronic device having a display screen, in accordance with a second embodiment. FIG. 3 illustrates a front view of an electronic device having a display screen, in accordance with a third embodiment. FIG. 4 illustrates a front view of an electronic device having a display screen, in accordance with a fourth embodiment. FIG. 5 illustrates a front view of an electronic device having a display screen, in accordance with a fifth embodiment; and, FIG. 6 illustrates a front view of an electronic device having a display screen, in accordance with a sixth embodiment. The outer rectangular broken line in each drawing shows a display screen of an electronic device. The other broken lines showing portions of the graphical user interface form no part of the claimed design.
